FINGER RING HOLDER
 Wesley R. Door, 316 W. Kennewick Ave.,
 Kennewick, Wash.
 Filed Aug. 27, 1959, Ser. No. 836,377
 1 Claim. (Cl. 113—99)

This invention relates to a finger ring holder to grip one or more rings or ring findings during manufacture or repair.

In jewelry practice it is often necessary to grip a ring to repair or resize it or to grip a wedding and engagement ring ensemble together to solder them to each other. It is also necessary to clamp ring findings while the ring is being assembled. To accomplish this, the common practice is to wire the rings together or to use a charcoal block and tweezers to hold the parts. This arrangement makes alignment extremely difficult and requires a great deal of time.

It is an object of this invention to provide a simple ring holder which is portable and which will securely grip one or more rings regardless of size.

It is another object of this invention to provide a ring holder which will hold a ring and a ring finding during assembly.

These and further objects will become apparent from the following description and accompanying drawings. It is to be noted that the embodiments shown are not exhaustive, but merely illustrate one form of this invention.

In the drawings:

FIGURE 1 is a front elevational view of the novel finger ring holder;

FIGURE 2 is a side elevational view of the novel finger ring holder;

FIGURE 3 is a sectional view taken on line 3—3 of FIGURE 1 showing the lower section of the handle broken away for convenience;

FIGURE 4 is a view similar to FIGURE 1 with the lower section of the holder shown in section;

FIGURE 5 is an enlarged front elevational view of the upper section of the holder showing two rings being held in place;

FIGURE 6 is a top view of the finger ring holder;

FIGURE 7 is a front elevational view of the upper portion of a second embodiment of the finger ring holder showing a ring and finding in position on the holder; and

FIGURE 8 is a sectional view of the holder in FIGURE 7 taken along line 8—8.

Referring now to the drawings there is shown a ring holder consisting of a handle 10, a sleeve 11, two jaws 12 and a flat spring 13. The handle 10 is made of plastic or metal, may be solid or hollow and may have any desired outside configuration. In the drawings handle 10 is shown as a solid cylindrical piece of bar stock. Handle 10 has an opening 14 at its upper end extending into the end of the bar stock and terminating in a shoulder 15. At the lower end of opening 14 is a threaded hole 16 which extends along the center of the cylindrical handle 10.

Two jaws 12 form a clamp generally denoted as 32. The jaws 12 are formed of steel wire and have flattened ends 17 containing holes 18. A threaded shaft 19 also has a flattened extension 20 through which a hole 21 is cut. A small rivet 22 connects jaws 12 and shaft 19 through holes 18 and 21 to form a hinge. The lower end of shaft 19 is threaded at 23 and is received by threaded hole 16.

The hinged portions of the jaws 12 are surrounded by a cylindrical sleeve 11 which is hollow and is squeezed and spread at its top portion 24 to hold jaws 12 in a

2

vertical plane and to allow movement of jaws 12 within this plane. Sleeve 11 also has a rounded lower end 25 which abuts against shoulder 15. The diameter of opening 14 and outer diameter of sleeve 11 are nearly identical to allow handle 10 to rigidly support sleeve 11.

The jaws 12 are mirror images of one another and therefore only one jaw will be completely described. Each jaw 12 has a straight portion 26 extending from its flattened end 17. This portion 26 is bent inwardly at 27 and has an inwardly extending straight portion 28. A flat spring 13 having notches 29, which fit around jaws 12, fits between jaws 12 at bends 27 to urge the jaws 12 apart. It can be seen in FIGURE 1 that portions 26 and 28 form a diamond shaped configuration, with portion 28 being somewhat shorter than portion 26.

The straight portion 28 is curved outwardly at 30 and inwardly again as 31 to complete the clamp 32. This clamp has two elements 33, 34 at each side which are joined in a transverse inverted U shape. Sides 33, 34 are bent outwardly from a line parallel with portion 28. The side 34 terminates in a hooked prong 35 which is bent sharply inward.

From this description it can easily be seen that as shaft 19 is threaded into handle 10 the top portion 24 of sleeve 11 will force clamps 32 toward each other. As shaft 19 is retracted, spring 13 will force the clamps 32 apart, limited by the abutment of portions 26 on sleeve 11 at portion 24.

In use, a ring is placed horizontally between clamps 32 which are then closed by turning handle 10 until secure gripping contact is made with the ring at four points by elements 33, 34 of each clamp 32. The ring is further supported by hooked prongs 35 which prevent the ring from slipping toward hinge rivet 22. The clamps 32 are wide enough to accommodate a plurality of rings, such as a wedding band 36 and engagement ring 37 as shown in FIGURE 5, to hold them securely while soldering them together. Whether the rings are of the same size or not is immaterial since the steel clamps 32 can bend to grip a plurality of sizes at once. This provides a steady working grip for rings while soldering, repairing, resizing or assembling. The open configuration of the holder allows free heat transfer and the handle 10 may be gripped by hand, in a socket or in a vise during usage.

A slightly different configuration of the holder is shown in FIGURES 7 and 8 wherein the holder is adapted to grip a ring finding 38 and a ring 39 for assembly purposes. The main structure of the holder is identical with that previously described. Clamp 40 is identical in shape to clamps 32 in FIGURES 1-6 but has prong 35 positioned close to jaw 12 (see FIGURE 8). Clamp 41 has a somewhat sharper outward bend at 42 than the corresponding bend in clamp 40. The bend 42 extends a short distance to a narrow U-shaped channel 43 the outer side of which extends almost parallel to portion 28 and is labeled 44. Side 44 is bent at a right angle and is shaped to overlap the ring at 45 and hooks downward and inwardly at 46, terminating in an inside portion 47 also overlapping the ring. The channel 43 and portion 47 are wide enough to accommodate a single band or ring.

During assembly, the finding 38 is placed upon hooked prong 35 and the ring 39 fits within channel 43 and hook 46 being held in a single plane by side 44 and portion 47. This will align the parts 38 and 39 and by turning the handle 10 the two parts will be brought into proper position and held securely for soldering.

From the foregoing it is evident that this holder allows ultimate freedom of access to the rings for work and yet is easily secured or released by simply turning handle 10.

The two embodiments shown are illustrative only, and are not intended to limit the scope of this invention except as it is limited by the claim which follow.

Having fully described this invention, I claim:

In a finger ring holder, a supporting handle, a pair of movable jaws mounted at one end of said handle, said jaws each comprising a continuous length of bent rod mounted on the handle for movement both relative thereto and toward or away from one another, said jaws including a straight portion directed angularly outward from the handle and from one another, said jaws further including a bent U-shaped portion extending angularly inward toward one another and means connecting said U-shaped portion to the outer end of said straight portion, the open end of the U-shaped portion being faced

toward the handle, said U-shaped portions each terminating in a hook directed angularly inward toward one another and away from the handle.
